Primary Examiner—Doris V. Coles[57] **CLAIM**

The ornamental design for the combined knife and scabbard, as shown and described.

DESCRIPTION

FIG. 1 is a front elevational view of the combined knife and scabbard showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view thereof showing the knife inside the scabbard.

The scallops on the knife scabbard in FIG. 1 represent tooling on the surface of the leather.
